INVENTOR:

Augustus W. Stephens

UNITED STATES PATENT OFFICE.

AUGUSTUS W. STEPHENS, OF CAMBRIDGE, MASSACHUSETTS.

DESIGN FOR A BOTTLE-SEAL REMOVER.

SPECIFICATION forming part of Design No. 34,096, dated February 19, 1901.

Application filed January 21, 1901. Serial No. 44,231. Term of patent 3½ years.

To all whom it may concern:

Be it known that I, AUGUSTUS W. STEPHENS, of Cambridge, in the county of Middlesex and State of Massachusetts, have invented and produced a new and original Design for a Bottle-Seal Remover, of which the following is a specification, reference being had to the accompanying drawing, forming a part thereof.

10 In the accompanying drawing my new design is shown in side elevation.

15 The essential feature of my design is a flat-sided plate having the parallel edges 2 3, the longer curved edge 4, extending from the edge 2, the shorter curved edge 5, extending from

the edge 3, the J-shaped edge 6, extending between the ends of the curved edges 4 and 5, the partially-elliptical edge 7, extending between the edges 2 and 3, and an orifice 8 within the edge 7.

20

I claim—

The design for a bottle-seal remover, substantially as shown and described.

In testimony whereof I have affixed my signature in presence of two witnesses.

AUGUSTUS W. STEPHENS.

Witnesses:

C. F. BROWN,
M. B. MAY.
